Primary Examiner—Doris V. Coles
Attorney, Agent, or Firm—Jim Zegeer, Esq.

[57] **CLAIM**

The ornamental design for a tick remover, as shown and described.

DESCRIPTION

FIG. 1 is a perspective view of a tick remover in the folded position, showing my new design;

FIG. 2 is a right side elevational view in the open position, the left side being a mirror image thereof;

FIG. 3 is a bottom plan view thereof; and,

FIG. 4 is a top plan view thereof.
